SOUND RECORDING APPARATUS

Ulrich L. di Ghilini, deceased, late of Beverly Hills, Calif., by Alexander E. di Ghilini and Leo E. di Ghilini, administrators, Beverly Hills, Calif., assignors, by decree of court, of one-third to Alexander E. di Ghilini, one-third to L. Elston di Ghilini, and one-third to Leo W. Petroff

Application April 5, 1948, Serial No. 19,106

15 Claims. (Cl. 274—12)

1

This invention relates to an apparatus for recording and reproducing sound on and from a disk record, and refers particularly to an apparatus of the type in which a constant groove speed is maintained relative to the stylus.

One object of the present invention is to provide an apparatus of the above-described class, in which an improved arrangement is included for driving the turntable by means of a friction wheel, the apparatus being characterized by the fact that the carriage is provided with a fork portion through which the drive shaft extends, and by which the carriage is partially supported. The apparatus is further characterized by the fact that a roller is positioned in this fork keyed to the drive shaft carried axially by the movement of the carriage, the friction wheel being adapted to be squeezed between this roller and the turntable in driving position. By this construction of the carriage and arrangement for driving the turntable through the friction wheel, it is found that a markedly superior recording operation is effected.

Another object of the present invention is to provide an improved stylus arm mounting and control apparatus. The stylus arm and control apparatus of the present invention is characterized by the fact that it is movable into three positions: one, a release position for shifting the carriage where the arm is elevated from the turntable; two, a play-back position where the stylus arm is substantially locked to the carriage so as to be bodily radially moved with the movements of the carriage, the stylus arm, however, being permitted a slight freedom of rotation about a vertical axis equivalent to moving the stylus to small numbered, two or three, groove widths; and a third position intended for recording, in which the entire weight of the arm is disposed upon the stylus and all freedom of movement of the arm about a vertical axis is prevented, so that the arm is positively locked for bodily movement with the movement of the carriage; and in which the weight imposed in this recording operating position is adjustable. The apparatus is further characterized by the fact that through the movement of a single control lever the stylus arm may be moved to these respective positions while at the same time the driving means for the turntable and carriage are controlled.

2

Various further objects and advantages of the invention will be apparent from the following description of a preferred example of an apparatus embodying the invention, a description being given in connection with the accompanying drawings, in which:

Figure 1 is a fragmentary plan view with the turntable broken away.

Figure 2 is a side view with the turntable in place.

Figure 3 is an enlarged section mainly on the line 3—3 of Figure 1, but with the casing of the head partially in section.

Figure 4 is a fragmentary section substantially on the line 4—4 of Figure 1.

Figure 5 is a fragmentary side view of Figure 4.

Figure 6 is a fragmentary section on the line 6—6 of Figure 3.

Figure 7 is a fragmentary section on the line 7—7 of Figure 3.

Figure 8 is a fragmentary side view of the stylus arm.

Figure 9 is a section on the line 9—9 of Figure 8.

Figure 10 is a side view of a lock employed in Figure 9.

Figure 11 is a fragmentary section on the line 11—11 of Figure 1.

Figure 12 is a fragmentary section on the line 12—12 of Figure 11.

Referring to the drawings, the apparatus comprises a turntable 2, which is adapted for supporting a disk 3 of suitable material, such as plastic, upon which recordings are to be made. The turntable 2 is attached to an axle 4 and is rotatably mounted by the frame 5. The axle 4 has a worm 6, which engages a worm wheel attached to a horizontal shaft 7. The shaft 7 has its major portion threaded as indicated at 8, and as later described, serves as an advancing screw for the carriage of the apparatus.

The carriage comprises a main body member 9, which is supported by a drive shaft 10 and a rod 11. The rod 11 is mounted by bearings 12 in the frame 5, so as to be axially slidable through said bearings, and is rigid with the body 9 of the carriage so as to move therewith, being held thereto by the set screw 13. The drive shaft 10 is mounted by bearings 14 supported by the frame 5 and is provided with a pulley 15 by means

of which it may be driven. The portion of the drive shaft 10 between the sides of the frame 5 is provided with a slot 16 intended to act as a key way. As illustrated more clearly in Figure 7, the body member 9 of the carriage is bifurcated, mounting spaced apart bearings 17 and 18 receiving the drive shaft 10.

To the body member 9 of the carriage there is mounted a roller member, which comprises a sleeve 19, which may be of metal, the ends of which have a bearing contact with the sides of the bifurcation of the member 9. On the exterior of this sleeve 19 is mounted a cylinder 20, which may be of slightly reduced width, which provides a smooth cylindrical outer surface. This cylinder 20 is preferably formed of material such as fiber, plastic or rawhide, which will offer a resistance to slippage to the friction wheel hereafter described. In order to provide for keying this roller member to the slot 16 of the drive shaft 10, and to also provide for its assembly in its intended operating position between the bifurcations or forks of the body member 9, there is provided a U-shaped key 21. This U-shaped key is of metal of a width corresponding to that of the slot 16, and is mounted in a radial slot through the sleeve 19. The central portion 22 of the U-shaped key 21 is of a width to allow radial movement of the key from the position shown in Figure 7 to an outer position, where it will clear the shaft 10 and thus allow for assembly of the apparatus. By this construction the roller member is carried axially of the drive shaft 10 by movements of the carriage, but rotates smoothly with the rotation of the drive shaft 10.

One of the bifurcations of the body member 9 of the carriage is again bifurcated, as indicated at 23, to mount a pin 24, to which is pivoted an arm 25, which, as illustrated in Figure 3, carries a threaded shoe 26 for engagement with the underside of the threaded portion 8 of the feed screw 7, so as to cause an axial movement of the carriage 9 with the rotations of the feed screw. The arm 25 is yieldingly urged into position to contact the feed screw by the spring 27, and is provided with a face 28 which, as hereafter explained, is used for moving the arm to a retracted position.

The body 9 of the carriage is provided with a vertical slot 28a which receives a friction wheel arm 29, which arm and its outer end are bifurcated to provide a mounting for a pin 30, upon which is journaled a friction wheel 31. The friction wheel 31 preferably comprises two metallic side members 32, between which is clamped a member 33 of suitable friction material such as rubber. The arm 29 is pivotally mounted on a rod 34 which is slidable in elongated slots 35 in the body member 9, which slots are in a horizontal direction, so that the friction wheel and arm 29 are movable from the position shown in Figures 3 and 4 to the right. In the position shown in Figures 3 and 4 the friction wheel has dropped from contact with the underside of the turntable 2 and from contact with the cylinder 20. There is provided a stop 36a on the body, which in the position shown in Figures 3 and 4 limits the lowering of the friction wheel. On movement to the right the friction wheel 31 is brought into engagement with the cylindrical roller 20 and raised slightly so as to bring it in contact with the underside of the turntable 2. The friction wheel is yieldingly urged to this operating position by springs 36 located on opposite sides of the body 9 of the carriage. The

movement of the friction wheel and arm 29 to the release position shown in Figures 3 and 4 is under control of a rod 31, which is actuated by control mechanism hereafter described.

The body 9 of the carriage has an upwardly extending portion or mounting post 38, the lower portion of which is vertically slotted as indicated at 39. On the upper end of this mounting post is positioned a plate 40, and a pin 41 pivotally supports one end of the plate 40 on the mounting post 38, the pin being mounted at bearing 42. A second pin 43 is axially movable through a vertical opening in the mounting post 38 and has a tapered upward end 44 of slightly reduced diameter. This pin 43 is yieldingly urged downwardly by a spring 45 held to the plate by the set screw 46. In the position illustrated in Figure 4 the plate 40 is capable of undergoing a rotation about the pivot pin 41 of a few thousandths of an inch, because the tapered portion 44 of the pin 43 only is in engagement with the plate 40. As later described, the pin 43 may be moved upwardly to positively lock the plate 40 against any movement relative to the post 38. There is also provided a spring lock 46a for holding the plate 40 down against the surface of the mounting post 38.

The plate 40 has a pair of downwardly turned ears 47. A stylus arm 48, as illustrated in Figure 6, is pivotally mounted on these ears by means of set screws 49. This stylus arm is preferably weighted, as indicated at 50, by means of a lead weight, and to the stylus arm is pivoted a head 51 carrying a stylus 52. The head 51 may be any usual electrical pick-up for generating electric currents from vibration of the stylus 52 or for vibrating the stylus 52 in response to currents passed to the head 51. Above the head 51 is provided a coil spring 52a which acts as a cushion in moving the apparatus but does not materially load the head in operation. The head 51 is provided with a set screw 53, which operates to lock stylus 52 in position as well as a stop to limit the head's downward movement. The head 51 is pivoted, as indicated at 54, to the arm 48 by a locking device illustrated in Figures 9 and 10. Said locking device comprises a rod 55 adapted to be turned by the knob 56, which rod carries a pin 57 working in a J-slot of a sleeve 59, said rod having a flange 60 at its end. In installing the head 51 the sleeve 59 is inserted in the head 51 which is then moved in position with the slot in a plane parallel to the long axis of head 51 and facing towards stylus 52, whereupon the rod 55 is passed axially through the sleeve. It is then turned clockwise 25° so as to cause pin 57 to move in the J-slot so as to lock the parts from axial but not vertical movement, the rod 55 then being locked in a set position by the set screw 58. The J-slot should have about a 90° arc.

The mechanism of the present invention is movable to three operating positions. In one operating position the apparatus is intended for recording. In the second operating position the apparatus is intended for playing back records previously recorded. In the third operating position (which is illustrated in the drawings) the apparatus is retracted to allow for shifting of the carriage. To condition the various elements so that they may be simultaneously moved to these three different operating positions, a cam member 76 is pivoted on a pin 71 extending through the slot 39 of the body 9 of the carriage. This cam has a cam portion 72 for cooperation with the rod 43 for elevating the rod 43 as the cam turns

counterclockwise, as viewed in Figure 4, after a short period of rotation of the cam 70. The cam 70 has a side face 73, which is in sliding contact with a collar 74 on the rod 37. It is the contact between this face and the collar 74 which moves the friction wheel arm 29 to the release position as shown in Figure 4. As the cam member 70 is rotated counterclockwise it allows the springs 36 to pull the friction wheel arm 29 into the operating position. The cam member 70 is also provided with a surface 75, which is a segment of a cylinder with the center at the center of rotation of the cam 70. This surface 75, in the position shown in Figure 4 of the drawings, is in contact with a roller 76 carried by an arm 77. The arm 77 is pivoted, as indicated at 78, to the carriage and is attached to a spring 79, which is in turn attached through an adjustment device 80 to the stylus arm 48. When the cam 70 has been rotated a sufficient distance to disengage the roller 76, the arm 77 may pivot upwardly to partially release the tension of spring 79 in holding the stylus arm 48.

The axle 71, which is rigid with the cam 70 through the use of a set screw 81, is provided at one side of the post 38 with an enlargement carrying the operating handle 82. The enlargement also is provided with a segmental cylindrical surface 83, which in the position illustrated, for example, in Figure 3 of the drawings, is in contact with an extension 84 of the stylus arm 48, so as to elevate said arm. On counterclockwise rotation of the cam 70, the cam face 83 releases the extension 84 to permit the arm 48 to drop downwardly as indicated, for example, in Figure 8. In order to latch the mechanism in the three intended operating positions, the shaft 71 is provided, on the opposite side of the post 38 from the operating handle, with a latching device comprising the crank member 85, which carries a spring compressed ball 86 in position to successfully engage three depressions 87 in a small plate 88 held to the post 38 by set screws 89.

In operation of the apparatus of the present invention, the control handle 82 may be moved first to the releasing position in which the parts are shown in most of the figures of the drawings. In this position the stylus arm is held upwardly by contact between the face 83 and the extension 84 of the stylus arm. The face 75 of cam 70 presses on roller 76 to increase tension on spring 79 to aid in raising arm 48. Likewise, the friction wheel arm 29 is shoved to the left, as viewed in Figure 4, by contact of the cam 70 with the collar 74 so as to release the friction wheel both from the roller 20 and from the underside of the turntable 2. This motion, through the contact between the pin 34 and face 28 of the arm 25 pivots that arm counterclockwise to release the shoe 26 from the advancing screw. The apparatus is thus disengaged and the carriage may be slid radially with respect to the record to any desired position.

When the control handle 82 is rotated to the second operating position, the contact between extensions 83 and 84 is altered through the curvature of 84 so as to allow the arm 48 to assume a horizontal position. In this position only the weight of the head 51 will be imposed on the stylus. The desired weight for play-back is thus controlled by the manufacture of the head. The rotation of the cam 70 to this second operating position has likewise allowed the friction wheel arm 29 to be drawn back into this operating position, so that the friction wheel 31 is in simultaneous

engagement with the roller 20 and the underside of the turntable 2. Simultaneously, the arm 25 has been released so that its spring 27 may bring the drive shoe 26 into contact with the advancing screw. In this position the apparatus is in condition for reproducing records previously recorded.

When pulley 15 is rotated at constant speed, the roller 20 is rotated at constant speed, which in turn drives the friction roller 31 at constant speed. This friction wheel 31 is mounted so as to engage the turntable 2 at a point in substantially radial alignment with the stylus 52. In operation, therefore, linear groove speed recording and play-back is effected independent of the radial position of the stylus 52 with respect to the center of the turntable 2.

In play-back operations the stylus arm 48 is carried radially of the turntable bodily with the movement of the carriage 9. The position of the stylus arm and the stylus 52 relative to the carriage is very nearly rigid except about a horizontal axis, so that the work of moving the stylus arm is not imposed upon the record. However, a slight freedom of movement about a vertical axis is desirable in play-back operations and, accordingly, in this position the tapered end 44 of the pin 43 will allow a movement of the stylus corresponding to two or three groove widths of recording.

By further counterclockwise rotation of cam 70, through movement of the arm 82, the apparatus is conditioned for recording. The contact between 83 and 84 is now discontinued so as to allow the arm 48 to drop and impose its weight on head 51. The head becomes rigid with arm 48. The weight imposed on the stylus is now regulated by the adjustment device 80, since part of the weight of the arm is counterbalanced by spring 79. By such movement the face 72 of cam 70 is brought into contact with pin 43 so as to elevate that pin and now lock the plate 40 rigid with respect to the carriage, whereby the stylus arm 48 is rigid except for movement about the horizontal axis of members 49, so that the stylus arm 48 has no rotation about any vertical axis. Simultaneously, the face 75 of cam 70 releases roller 76 to bring spring 79 into a desired operative position. Thereby, the entire weight of the arm 48 is available to be imposed upon the stylus 52, spring 52^a being substantially compressed and spring 79 now counterbalancing arm 48.

By the apparatus herein described, it is possible to record and reproduce messages on records in which many times the usual lines per inch are recorded and reproduced from the same record, greatly increasing the recording and play-back time of a record of given size. These improvements in operation are dependent to considerable extent on the novel manner by which the friction wheel 31 is able to drive the turntable 2 by direct contact between it and the roller 20, which is rigid with the drive shaft as far as rotary movement is concerned, but which moves axially with the carriage so as to always present the same surface to the friction wheel 31. In effecting recordings of this type in recording and play-back operations, where recording of a great number of lines per radial inch of record are carried out, it is necessary that the operation of the arm which carries the stylus be positively controlled. The movement of the arm as the recordings proceed radially with respect to the record must be positively operated rather than be under control of pressure from the grooves on the disk. Ac-

Accordingly, in play-back operations this arm is bodily carried with the carriage, yet in these play-back operations a very slight freedom of movement in the nature of two or three groove widths must be provided for at the stylus point, while in recording operations an absolute freezing of the stylus to the carriage with respect to motion about a vertical axis is necessary. The apparatus of the present invention provides this type of control over the stylus arm by an accurate control of the relative weights to be imposed on the stylus during recording and play-back operations, and further accomplishes these adjustments through the operation of a single control member.

While the particular examples of the apparatus of the present invention herein specifically described have in practice been found well adapted for carrying out the objects of the invention, it is to be understood that various modifications and changes may be made, and this invention is of the scope set forth in the appended claims.

It is claimed:

1. An apparatus for recording and reproducing sound on a disk record of the type in which a turntable is rotated by a friction wheel moved radially of the turntable by a carriage which in turn is advanced by an advancing screw driven by the turntable, the carriage carrying a stylus arm, such apparatus being characterized by a drive shaft upon which the carriage is partially supported and mounted for movement axially of the drive shaft, the drive shaft having a key way and the carriage being slotted where the drive shaft extends through the carriage, a roller keyed to the drive shaft and positioned in said slot and in contact with the side walls thereof so as to move axially of the drive shaft with the carriage, and means for mounting the friction wheel on the carriage so that it is movable to and from the position where it is yieldingly pressed simultaneously against said roller and said turntable.

2. An apparatus for recording and reproducing sound on a disk record of the type in which a turntable is rotated by a friction wheel moved radially of the turntable by a carriage which in turn is advanced by an advancing screw driven by the turntable, the carriage carrying a stylus arm, such apparatus being characterized by a drive shaft extending through said carriage and upon which said carriage is partially mounted for movement axially of the drive shaft, said carriage having a slot in the portion thereof through which the drive shaft extends, the drive shaft having a key way, a roller keyed to the drive shaft and disposed in said slot in engagement at its ends with the walls thereof so as to move axially with the movement of said carriage, an arm carrying said friction wheel in position to maintain the same in the same axial alignment with said roller, said arm being movable to and from the position where said friction wheel is in simultaneous contact with said turntable and said roller.

3. An apparatus for recording and reproducing sound on a disk record of the type in which a turntable is rotated by a friction wheel moved radially of the turntable by a carriage which in turn is advanced by an advancing screw driven by the turntable, the carriage carrying a stylus arm, such apparatus being characterized by a drive shaft extending through said carriage and upon which said carriage is partially mounted for movement axially of the drive shaft, said carriage having a slot in the portion thereof through which

the drive shaft extends, the drive shaft having a key way, a roller keyed to the drive shaft and disposed in said slot in engagement at its ends with the walls thereof so as to move axially with the movement of said carriage, an arm carrying said friction wheel in position to maintain the same in the same axial alignment with said roller, said arm being movable to and from the position where said friction wheel is in simultaneous contact with said turntable and said roller, and means for yieldingly urging said arm and friction wheel into said position.

4. An apparatus for recording and reproducing sound on a disk record of the type in which a turntable is rotated by a friction wheel moved radially of the turntable by a carriage which in turn is advanced by an advancing screw driven by the turntable, the carriage carrying a stylus arm, such apparatus being characterized by a drive shaft which extends through a portion of said carriage, upon which said carriage is partially supported for movement axially of said drive shaft, said portion of said carriage having a slot, and said drive shaft having a key way, a roller member disposed in said slot and keyed to said drive shaft, said roller including a sleeve in bearing contact with the side walls of said carriage and a cylinder member on said sleeve of friction material, and means for supporting said friction wheel on said carriage for movement to and from a position in which said friction wheel is in simultaneous contact with said cylinder member and said turntable.

5. An apparatus for recording and reproducing sound on a disk record of the type in which a turntable is rotated by a friction wheel moved radially of the turntable by a carriage which in turn is advanced by an advancing screw driven by the turntable, the carriage carrying a stylus arm, such apparatus being characterized by a drive shaft which extends through a portion of said carriage, upon which said carriage is partially supported for movement axially of said drive shaft, said portion of said carriage having a slot, and said drive shaft having a key way, a roller member disposed in said slot and keyed to said drive shaft, said roller including a sleeve in bearing contact with the side walls of said carriage and a cylindrical member on said sleeve of friction material, and means for supporting said friction wheel on said carriage for movement to and from a position in which said friction wheel is in simultaneous contact with said cylinder member and said turntable, said roller member including a U-shaped key, the sleeve of said roller member having a radial slot in which said key is radially mounted.

6. In an apparatus for recording and reproducing sound on a disk record of the type in which a turntable is rotated by a friction wheel moved radially of the turntable by a carriage which in turn is advanced by an advancing screw driven by the turntable, a carriage carrying a stylus arm characterized by means for mounting the stylus arm on said carriage, which means includes a member to which said stylus arm is pivoted for rotation about a horizontal axis, said member being mounted on said carriage for a limited movement of a few groove widths of said stylus about a vertical axis, means for restricting said movement of said member relative to said carriage, said means including a tapered pin carried by said carriage and movable within said carriage and into a hole in said member and having a portion fitting said hole without clearance for

thus locking said member and said carriage together, and means mounted on said carriage including a movable element engaged with said pin for moving said pin into locking engagement with said member.

7. In an apparatus for recording and reproducing sound on a disk record of the type in which a turntable is rotated by a friction wheel moved radially of the turntable by a carriage which in turn is advanced by an advancing screw driven by the turntable, a carriage carrying a stylus arm characterized by means for mounting the stylus arm on said carriage, which means includes a member to which said stylus arm is pivoted for rotation about a horizontal axis, said member being mounted on said carriage for a limited movement of a few groove widths of said stylus about a vertical axis, and means for restricting said movement of said member relative to said carriage, said means including a tapered pin carried by said carriage and movable within said carriage and into a hole in said member and having a portion fitting said hole without clearance for thus locking said member and carriage together, a movable element mounted on said carriage and engaged with said pin for moving said pin into locking engagement with said member, an adjustable spring device for controllably counterbalancing the stylus arm, and operating means for simultaneously releasing said spring device with prearranged recording tension and actuating said movable element for locking said member to said carriage.

8. In an apparatus for recording and reproducing sound on a disk record of the type in which a turntable is rotated by a friction wheel moved radially of the turntable by a carriage which in turn is advanced by an advancing screw driven by the turntable, a carriage carrying a stylus arm characterized by a member mounted on said carriage to which said stylus arm is pivoted for movement about a horizontal axis, said member having an opening receiving a tapered pin mounted for vertical movement by said carriage, said tapered pin having a portion allowing a limited movement of the stylus arm about a vertical axis and having a portion fitting the opening in said member for locking the stylus arm against movement about a vertical axis with respect to said carriage, a spring tension counterbalancing means for said stylus arm, and a control member rigid with cam means including a cam portion for vertically moving said tapered pin and releasing said spring device.

9. In an apparatus for recording and reproducing sound on a disk record of the type in which a turntable is rotated by a friction wheel moved radially of the turntable by a carriage which in turn is advanced by an advancing screw driven by the turntable, a carriage carrying a stylus arm characterized by a member mounted on said carriage for a limited movement about a vertical axis, said member having an opening, a tapered pin mounted upon said carriage for vertical movement into said opening and having a retracted position in which it allows such limited movement of said member and an advanced position in which it prevents the same, and means on said carriage including a movable element engaged with said pin for advancing said pin vertically from its retracted position into locking engagement with said member, said stylus arm being pivoted to said member about a horizontal axis, said stylus arm pivotally supporting about a horizontal axis a recording head.

10. In an apparatus for recording and reproducing sound on a disk record of the type in which a turntable is rotated by a friction wheel moved radially of the turntable by a carriage which in turn is advanced by an advancing screw driven by the turntable, a carriage carrying a stylus arm characterized by a member mounted on said carriage for a limited movement about a vertical axis, said member having an opening, a tapered pin mounted upon said carriage for vertical movement into said opening and having a retracted position in which it allows such limited movement of said member and an advanced position in which it prevents the same, means on said carriage including a movable element engaged with said pin for advancing said pin vertically from its retracted position into locking engagement with said member, said stylus arm being pivoted to said member about a horizontal axis, said stylus arm pivotally supporting about a horizontal axis a recording head, and a releasable spring device for counterbalancing said stylus arm.

11. Apparatus as defined in claim 7, including an extension carried by the stylus arm and a cam engageable with said extension for rotating said stylus arm about its horizontal axis to raise and lower the stylus arm relative to the turntable, and in which the operating means also rotates said cam to effect lowering of said stylus arm simultaneously with the releasing of the spring device and the movement of the tapered pin into locking position.

12. In an apparatus for recording and reproducing sound on a disk record of the type in which a turntable is rotated by a friction wheel moved radially of the turntable by a carriage which in turn is advanced by an advancing screw driven by the turntable, a carriage carrying a stylus arm characterized by means for mounting the stylus arm on said carriage, which means includes a member to which said stylus arm is pivoted for rotation about a horizontal axis, said member being mounted on said carriage for a limited movement of a few groove widths of said stylus about a vertical axis, means for restricting said movement of said member relative to said carriage, said means including a locking element carried by said carriage and movable relative to said carriage and into interlocking engagement with said member for locking said member and said carriage together against relative movement, and operating means mounted on said carriage including a movable element engaged with said locking element and actuatable for moving said locking element into locking engagement with said member.

13. Apparatus as defined in claim 12, in which the member to be locked to the carriage carries spring means yieldably opposing movement of the locking element into locking position and normally maintaining the locking element engaged with the movable element.

14. Apparatus as defined in claim 12, including an extension carried by the stylus arm and a cam engageable with said extension for rotating said stylus arm about its horizontal axis to raise and lower the stylus arm relative to the turntable, and in which the operating means for actuating the movable element for moving the locking element into position is arranged to also actuate said cam to effect lowering of said stylus arm relative to said turntable.

15. Apparatus for recording and reproducing sound on a disk record, comprising: a turntable;

a carriage; means supporting said carriage for movement relative to said turntable; a drive roller carried by said carriage; a friction wheel also carried by said carriage and engageable with said drive roller and turntable for transmitting a drive from said roller to said turntable; a first means for effecting engagement of said friction wheel with said roller and turntable; a carriage advancing screw driven by said turntable; a movable shoe carried by said carriage and engageable with said screw for connecting said carriage with said screw for movement by said screw; a second means for effecting engagement of said shoe with said screw; a stylus arm pivotally mounted upon said carriage for movement toward and away from said turntable; a third means actuatable to control the position of said stylus arm relative to said turntable; and a control handle arranged to actuate said first means to engage said friction wheel with said roller to 20 drive said turntable, to actuate said second means to engage said shoe with said screw to effect

5

10

movement of said carriage relative to said turntable, and to actuate said third means to lower said stylus arm toward said turntable, all upon movement of said handle to a given position.

ALEXANDER E. DI GHILINI,
LEO E. DI GHILINI,
Administrators of the Estate of Ulrich L. di Ghilini, Deceased.
